UNITED STATES PATENT OFFICE

WILLIAM JAMES HADDEN, OF GLASGOW, SCOTLAND, ASSIGNOR TO DONALDSON MANUFACTURING COMPANY LIMITED, OF GLASGOW, SCOTLAND

ROLLER BLIND AND FITTING THEREFOR

Application filed September 24, 1927, Serial No. 221,674, and in Great Britain August 31, 1927.

This invention relates to roller blinds of the type including means (such, for instance, as a ratchet wheel held to the blind roller by friction) for permitting the blind to be lowered to and held in different positions while said means is held stationary, and refers also to the fittings for said roller blinds.

In my prior U. S. specifications Serial Nos. 190,326 and 203,145 there is described a roller blind of the above specified type provided, at one or both ends, with means for raising the blind, incorporating means for retracting, to its initial position, the cord which is operated in raising the blind. In one particular means for retracting the cord described, by way of example, in the said prior specifications, a coil spring is located between said means and a sleeve adapted, when in position, to be anchored against movement, by projections in the cover part of a fixed supporting bracket.

Now this arrangement is entirely satisfactory in use, but it is found in practice that it is not absolutely fool-proof, because, if the said cord retracting means is rotated in the wrong direction, due to some error in assembly, the coil spring may be broken.

The object of the present invention is to overcome this defect and to provide an arrangement which while being cheap and easily assembled will be absolutely fool-proof.

To this end, the present invention is characterized by anchoring means for the coil spring which is so arranged that when the retracting means is rotated in a direction to raise the blind by the cord, the coil spring anchoring means is stationary, but when the retracting means is rotated in the opposite direction, the said anchoring means can rotate therewith. This can be obtained by using a one-way clutch device, such as a ratchet and pawl.

A further object of this invention is to provide an improved manner of anchoring one end of the coil spring to the sleeve, and to this end, the sleeve is provided with two slots extending as chords across one end face of the sleeves, said slots being mutually perpendicular to each other and serving to receive one end of the spring.

Referring to the drawings:—

Fig. 1 is a longitudinal sectional elevation of the blind roller, illustrating an embodiment in which there are raising means at both ends. 55

Fig. 2 is a similar view of one end of the roller only, drawn to an enlarged scale.

Fig. 3 is a sectional view on the line 3—3 in Fig. 2.

Fig. 4 is a sectional view on line 4—4 in Fig. 2. 60

Fig. 5 is an end view of one part removed showing the improved manner of anchoring one end of the spring.

In the practical embodiment shown in the drawings the roller 1 to which the blind (not shown) is fixed, may be of any usual form. The end members are constructed as separate fittings each of which comprise a circular flanged disc 5 engaging and fixed by 65 screws 4 to the proximate end of the roller and an axially extending journal 3 which is formed with a shoulder 6 between its end and the disc and is screwed at its end 7. On this journal there is a loosely mounted ratchet 75 wheel 13 which is frictionally clutched to the journal by a spring washer 11 located between the shoulder 6 and a disc washer 12 in contact with the ratchet wheel 13. A cord drum 14 is located on the journal at the outer side 80 of the ratchet wheel, in contact with the side thereof, this drum being rotatably mounted on a sleeve nut 15 screwed upon the journal and being provided with two oppositely extending cylindrical flanges 16, 17 within 85 which there is fitted disc rings 18, 19, the one 19 at the outer end being removable. Between the drum and the inner disc ring 18 there is mounted a number of, say three, pawls 20 rockable on rivets 21 extending between the said drum flange and disc ring, and adapted to engage with the ratchet wheel. Within the outer flanged part 17 and rotatably mounted on the sleeve-nut 15 is a sleeve 22 between which and the said flanged 90 part is located a coil spring 23 anchored to the two parts. One end 24 of the spring 23 is passed through slots (not shown) in the flanged parts 17 and the other end 26 is passed through the slots 27—28 in the sleeve part 22. 95

100

These two slots extend as chords across the end of the sleeve part being perpendicular to each other. The end of the spring is also bent to correspond with the slots. By this arrangement endwise movement of the spring in the sleeve part is prevented, the end of the spring does not require to be softened before inserting it in the slots and the outer part of the spring lies flat against the outer side of the sleeve part. This sleeve part is made integral with a ratchet wheel 25 located on the outside of the disc ring 19 co-operating with a pawl 29. This end fitting is also enclosed in a two part cover 30, 31, one part 10 30 of which carries the pivot 32 of the pawl 29 and this part also carries a bearing spindle 34 which projects within the sleeve nut 15. The cord 35 which is adapted to wind around the part between the drum flanges, is secured 15 at one end by passing it through a hole 37 in one flange and knotting this end of the cord. The other end of the cord passes through a hole 38 in the cover part 30 and is preferably provided with a tassel 39 or other 20 25 similar device.

The ratchet wheel 25 and pawl 29 constitute a one-way clutch device so arranged that when the drum is rotated in a direction to raise the blind the ratchet wheel 25 and the 30 sleeve part 22 are held stationary by the engagement of the pawl 29 with the ratchet wheel 25 so that the coil spring is tightened but when the drum is rotated in the opposite direction the ratchet wheel 25 can trip the 35 pawl 29 and rotates with the drum.

The two part covers 30, 31 are made to fit detachably together so that the end fittings can be inspected and parts thereof adjusted, removed, changed and replaced. These 30 35 covers are provided with apertured lugs 40 by which they can be fixed to the window frame.

The sleeve nut 15 can be moved by screwing it more or less on to the journal and by 45 this means the tension of the spring washers can be adjusted. A grub screw 47 is provided in the sleeve nut, which when screwed against the journal serves to lock the sleeve nut in its adjusted position. By removing 50 the covers, the sleeve nuts and other parts can be readily adjusted, removed and changed or replaced.

Whereas, in the construction illustrated, the blind is provided at both ends with raising means, the two end members are of identical construction except that, the journal, sleeve nut and grub screw at the right hand end are provided with left hand threads and the same parts at the left hand end are provided with right hand threads to prevent these parts from unscrewing by the operation of the blinds. Where raising means is provided at one end only of the roller, means such as that described in my U. S. specification Serial Number 190,326 will be provided 55 60 65

at the opposite end of the roller for holding the blind against downward movement by friction.

It will be understood that considerable alteration can be made in the fittings without departing from the spirit of this invention. 70

I claim:

1. A roller blind having, a roller, a cord drum for rotating said roller to raise the blind, means for normally holding said cord drum stationary, means for holding said cord drum to the roller by friction, for permitting the blind to be lowered to and held in different positions while it is stationary, a coil spring on said cord drum, a sleeve part having two slots extending as chords across one end thereof and located mutually perpendicular to each other adapted to receive and anchor one end of said spring and means for holding said sleeve part stationary so that the spring is wound up when the drum is rotated to raise the blind whereby the cord drum is thereafter returned to its initial position unidirectional clutching means for rendering said spring effective for said return only when the cord drum is moved in a direction to raise the blind. 80 85 90

2. A roller blind comprising, a roller, having at each end thereof a journal with a shoulder, a ratchet wheel rotatably mounted on said journal, means between said shoulder and ratchet wheel for frictionally holding said ratchet wheel to said journal, a cord drum rotatably mounted at the other side of the ratchet wheel, a cord on said drum adapted to rotate said roller for raising the blind, pawls on said drum engaging said ratchet wheel, a casing enclosing said journal and its associated parts at one end, a coil spring secured at one end to said drum, ratchet and pawl anchoring means for the opposite end of said spring, adapted to be held stationary when said cord drum is rotated to raise the roller so as to cause said spring to return the cord drum to its initial position relatively to the casing whereby the cord is retracted to its initial position but allow the spring and anchoring means to rotate freely with the drum when the latter is rotated in an opposite direction and means for adjusting said friction holding means. 100 105 110 115

3. A roller blind comprising, a roller having at each end thereof a journal with a shoulder, a ratchet wheel rotatably mounted on said journal, a spring washer between said shoulder and said ratchet wheel for holding said wheel to the journal by friction for permitting the blind to be lowered to and held in different positions while the ratchet wheel is stationary, a drum rotatably mounted at the side of the ratchet wheel, a cord for rotating the drum, pawls on said drum engaging said ratchet wheel adapted to cause the drum when moved in one direction to rotate the journal while permitting it to move 120 125 130

in the opposite direction independently of said journal, a bearing fixed relative to said journal, a coil spring between said fixed bearing and said drum and ratchet and pawl means for clutching said coil spring to the bearing when the drum is rotated to raise the blind adapted to cause the coil spring to return the drum to its initial position but allow the coil spring to move relatively to the drum when the latter is rotated in an opposite direction; all the parts being so arranged that the blind can be raised by pulling the cord at either end and after the blind has been moved to a required position the cord is automatically retracted to its initial position downward movement of the blind being checked at one end while the raising means at the other end is being operated.

4. The combination with a roller blind having, a roller, means for restraining movement of the roller for lowering the blind but allowing free movement of the roller for raising the blind, roller rotating means adapted when moved in one direction to rotate the roller for raising the blind but when moved in the other direction to rotate independently of the said roller, resilient means adapted to return said roller rotating means to its initial position after it has been moved to raise the blind into the required position, of unidirectional clutching means for rendering said resilient means effective for said return only when the roller rotating means is moved in a direction to raise the blind.

5. The combination with a roller blind having, a roller, means for restraining movement of the roller for lowering the blind but allowing free movement of the roller for raising the blind, a cord drum adapted when moved in one direction to rotate the roller for raising the blind but when moved in the other direction to rotate independently of the said roller, a spring having one end attached to said cord drum and being adapted to return the cord drum to its initial position after it has been rotated to raise the blind into the required position by a pull on said cord, of a ratchet wheel freely pivoted relative to said cord drum and to which the other end of said spring is attached, and at least one pawl stationarily pivoted relative to said cord drum and in engagement with said ratchet wheel, whereby said spring is effective for said return only when the cord drum is rotated in a direction to raise the blind.

6. A roller blind having a roller and end fittings at each end therefor each end fitting comprising, a journal fixed to said roller, a ratchet wheel rotatably mounted on said journal, means for frictionally holding said ratchet wheel to said journal, a drum rotatably mounted on said journal, a cord for rotating the drum, pawls on said drum engaging said ratchet wheel, adapted when the drum is rotated by the cord to rotate the

roller, but allow the drum to rotate in the opposite direction independently of said roller, a casing adapted to be fixed to the window, a coil spring secured at one end to said drum, a freely mounted ratchet to which the other end of said coil spring is secured, and a fixed pawl co-operating with said ratchet, whereby the ratchet and the end of the spring secured thereto is adapted to be free to move with the drum in one direction but is held stationary when the drum is rotated to raise the blind so as to return the cord drum to its initial position relatively to the casing whereby the cord is retracted to its initial position, and means on the cord cooperating with said casing to act as a stop thereby retaining the cord drum in its initial position whereby the blind can be lowered by being pulled down and can be raised by pulling the cord at either end of the roller, downward movement of the blind being checked at one end while the raising means at the other end is being operated.

In testimony whereof I affix my signature.

WILLIAM JAMES HADDEN.
